INTERNAL COMBUSTION ENGINE
CARBURETORGeorge M. Bicknell, St. Louis, Mo., assignor to
Carter Carburetor Corporation, St. Louis, Mo.,
a corporation of Delaware

Application January 4, 1932, Serial No. 584,660

28 Claims. (Cl. 123—119)

This invention relates to carburetors for internal combustion engines, and more particularly to automatically controlling the temperatures of and ratios of fuel to air mixtures.

5 It is an object of this invention to produce a new and improved carburetor capable of automatically controlling the fuel to air ratio of mixtures as required by the engine in accordance with the temperature.

10 It is a further object of this invention to provide a means of controlling the fuel and air mixture ratio, particularly at low temperatures and for short periods immediately after the starting of the engine, in accordance with the position of 15 the throttle valve.

15 It is a further object of this invention to provide a device of the above character which also has a means of manually controlling the air to fuel ratio of mixture, irrespective of the automatic control.

20 It is a further object of this invention to provide a means of automatically controlling the temperature of the mixture in inverse ratio with the temperature of the engine.

25 Other objects and advantages will appear from the following description and claims taken in connection with the accompanying drawings in which like reference numerals refer to like parts.

Figure 1 is a somewhat diagrammatic view 30 showing an elevation of the carburetor, with parts in section and others broken away. It also shows a section of an exhaust pipe extension and a mixture heater with a conventional thermostatic coil attached.

35 Figure 2 is a side elevation of the carburetor shown in Figure 1 with parts broken away and others shown in section.

Figure 3 is a sectional view of the carburetor shown in line 3—3 of Figure 2.

40 Figure 4 is a plan view of the carburetor shown in Figures 1 to 3.

Figure 5 is a plan view of the mixture heater taken along line 5—5 of Figure 1.

45 Figure 6 is a sectional detail view of the choke valve and associated parts, with the valve in closed position.

Figure 7 shows the same parts as Figure 6, with the valve in a different position.

Figure 8 is a diagrammatic view of the throttle 50 and choke valve linkage.

The reference numeral 1 indicates the lower half of the main body member of the carburetor. This lower half is provided with a flange 2 by means of which it can be attached to the intake manifold of an internal combustion engine. The

upper half of the carburetor 3 is formed with a separate casting and suitably fastened to the lower half. The two halves of the carburetor form a downdraft mixing conduit extending therethrough comprising air inlet 4, air chamber 5, mixing chamber 6, and discharge outlet 7.

The air inlet 4 is controlled by choke valve 8 carried on shaft 9. This choke valve is made in two sections, one rigidly attached to the shaft 9, as indicated at 10, Figure 6, and the other section 10 11 hinged thereon. A spring 12 normally holds the two sections of the choke valve in line.

Section 11 has a projection 13 thereon, for limiting its closing movement so that the action of the spring 12 will be stopped when section 11 has been brought into line with section 10. A latch 14 is pivotally mounted on the solid section 10 and has a latch contact member 15 thereon for contacting with the wall of the air inlet, and projection 16 at the other end thereof for contacting with the projection 13 to limit the opening movement of the valve portion 11. The construction and operation of this valve is shown and claimed in the application of Kommer and Henning, Number 535,704, filed May 7, 1931 which matured 20 to Patent No. 1,894,354 granted January 17, 1933. 25

For normal and high speed operation, the fuel is supplied to the mixing conduit through a nozzle 17 and tip 18, which nozzle tip is formed integral with primary venturi 19. The primary 30 venturi discharges into the secondary venturi 20, and the secondary venturi discharges into the main venturi 21, as indicated in Figure 1. The discharge of the mixture from the carburetor is controlled by the throttle valve 22 carried on shaft 23, this shaft being arranged for manual operation in any convenient manner, as for instance by connecting a lever to the crank 60.

For low speed operation, fuel is supplied to the mixing conduit through port or nozzle 24 shown 40 in Figure 1. It will be seen that this port is bisected by the throttle valve when in the position shown in dotted lines in Figure 1, which is in the closed position. However, it will be understood that two separate ports interconnected with the 45 idle tube 25 may be used in lieu thereof.

Fuel is supplied to the nozzle 24 by means of idle tube 25, connecting passages 26—27, calibrated passageway 28, passage 29, and metering jet 30. Fuel to the main nozzle 17 is also supplied 50 from jet 30, passage 29, and the chamber 31, which surrounds the tube 25. Thus, it will be seen that the main nozzle 17 and the idle nozzle 24 receive fuel in common from jet 30 and are interconnected by the restricted passageway 28. The 55

jet 38 is controlled in accordance with the position of the throttle by means of the metering rod 32. The jet 38 takes its fuel from chamber 33 in which the fuel is maintained at a constant level 5 A—A by float 34 and needle valve 35. Fuel is supplied in a conventional manner to needle valve 35 through connection 36 by the usual fuel pump or gravity tank.

The accelerating pump 37 is operated from a 10 rock arm 38 which, in turn, is operated by the throttle valve through link 39 and operating arm 40. This pump is of well known construction, and is not shown in full detail.

To control the choke valve position and consequently the air to fuel ratio of the mixture, in accordance with the atmospheric temperature (in the instance of a cold engine), and in accordance with the automatically controlled temperature of a mixture heater to which heat is supplied by the exhaust manifold (in the instance of a motor in operation), a conventional thermostatic coil 41 of the usual bimetallic construction is provided. The inner end of this coil is rigidly mounted by means of shaft 42 to the mixture heater 43. 25

An enclosure 44 is provided to prevent, to some extent, the influence of passing air currents upon the thermostatic coil. The shaft 42 is preferably made of a material having high heat conductive 30 properties. The outer end of the thermostatic coil is free to move in a clockwise direction upon the application of heat, and is connected to choke valve shaft 8 by means of link 45, arm 46, and swivels 47—48. Mixture heater 43 may be of the conventional type—that is, a simple jacket about a conduit conveying exhaust gases.

To control the temperature of the mixture heater in accordance with the requirements of the engine, the plain butterfly type valve 49 40 mounted on shaft 50 is provided at the entrance of the mixture heater and in an extension of the exhaust manifold 51. This extension of the exhaust manifold may be connected to the main exhaust manifold in any suitable manner (not 45 shown); however, affecting only a parallel flow of the exhaust gas which may be by-passed upon the closing of the valve 49.

A weighted arm 52 weighted at 53 and fixed on shaft 50 normally holds the valve 49 in an open 50 position. A slot 54 in arm 52 is engaged during the clockwise motion of the free end of the thermostatic coil by a roller 55, thereby closing the valve 49. A stop lug 56 cast on the exhaust manifold extension 51 limits the clockwise rotation of 55 valve shaft 50 to the full open position of valve 49.

The proportioning of lever arms provides for a full opening movement of the choke valve prior to the engagement of roller 55 in slot 54 during a clockwise movement of the thermostat. A stop 60 57 prevents the further rotation of the choke shaft 8 beyond full open position of the choke valve. A cylinder 58 in which link 45 is slidably mounted provides for further motion of the thermostat against the compression of spring 59 therein.

To control the choke valve position and consequently the air to fuel ratio of the mixture in accordance with the position of the throttle 70 valve and consequently in accordance with the speed of the engine, an interconnecting link 60 pivotally and slidably mounted on arm 46 and pivotally mounted on arm 61, which is fixed to the throttle shaft 23, is provided.

75 To permit a sufficient opening of the throttle

valve during the starting of an engine without any corresponding opening action of the choke valve, a link 60 is slidably mounted in pivot 62, this free action, however, being limited by stop screw 63. The stop screw 63 also provides a means of adjusting the position of the throttle valve with respect to the position of the choke valve.

To provide a means of manually controlling the air to fuel ratio of the mixture, particularly in the full open and closed positions of the throttle valve, it will be seen that link 60 in the position shown in Figure 1 is at dead center with respect to arm 61 and shaft 23. In this position, the choke valve 8 is fully closed, and the throttle valve 22 is partially open. Any further clockwise or closing motion of the throttle valve will cause a slight opening of the choke valve against the spring action of the thermostatic coil, thus insuring the positive partial opening of the choke valve, 20 irrespective of the automatic controlling device, when the throttle is in a fully closed position.

With respect to the position of the throttle and choke valves shown in Figure 1, any counter-clockwise motion of the throttle valve will cause 25 an opening of the choke valve. It will be seen, however, that a full opening of the throttle valve or approximately 90 degrees travel from its full closed position will have opened the choke valve approximately only 45 degrees as diagrammatically indicated in Figure 8, this being partially due to the difference in positions of the link pivots with respect to a center line through the valve shafts, and partially due to the lost motion through that portion of the throttle valve's 30 travel from the fully closed position to the position shown in Figure 1.

The operation of the device shown in Figures 1 to 8 is as follows:

Upon starting a cold engine in an atmospheric 40 temperature which is at or below a degree requiring a fully closed position of the choke valve, the throttle valve will be set in the position shown in Figure 1, either manually by the operator or by any suitable mechanical or electric interconnection with the engine ignition switch. Fuel is drawn into the mixing conduit by suction through nozzle 17 and tip 18 at the most restricted portion of the primary venturi. As the engine fires and begins to run under its own power, the suction will 50 substantially increase, tending to draw downward and open the hinged section 11 of the choke valve against the tension spring 12. The spring 12 is so calibrated as to allow hinged section 11 to open far enough to admit sufficient air for continued operation of the engine during the period 55 of time required to obtain sufficient heat in the mixture heater to operate the thermostatic coil.

As the motor warms up, the thermostatic coil will move in a clockwise direction, opening the 60 choke valve slowly, the thermostat being so designed and subjected to exhaust heat as to have fully opened the choke valve by the time the motor has reached a temperature requiring the full capacity of air inlet 4. It will be seen that 65 the choke valve is free to move toward the open position, irrespective of the throttle interconnection 60, by reason of the slidable pivot 62. As the temperature of the motor and of the exhaust system, including the mixture heater, continues to 70 rise, and the thermostat continues in its clockwise motion, roller 55 mounted on the free end of the thermostat will engage the slot 54, causing a counterclockwise motion of shaft 50 and a closing of the heat control valve 49, and thereby 75

controlling the flow of heat to the mixture heater. The travel of the thermostat beyond the position at which the choke valve and link 45 are stopped by stop 57 will be permitted by the sliding action 5 of link 45 in cylinder 58 against the compression spring 59. Spring 59, being so designed to offer only sufficient resistance to compression to allow the operation of the choke valve and overcome any joint friction, is, however, substantially weaker than the coiled spring action of the thermostat.

Upon starting an engine, particularly a cold engine, the usual tendency of the operator is to accelerate the engine by manually opening the 15 throttle valve and thereby shortening the warming up period. It will be seen, however, that any substantial opening of the throttle valve beyond that position to which it has been adjusted to obtain the proper starting mixture will have a tendency 20 to lean out the mixture, due to the opening of the choke valve which is controlled by a link connection (described heretofore) to the throttle. This interconnection by link 39, however, reduces this tendency toward unduly leaning out the mixture by a corresponding opening of the 25 fuel metering valve. It will be understood, however, that the compensation is by no means complete, and the operator may control the mixture ratio during warming up to a very substantial extent 30 by operating the throttle valve.

I claim:

1. In a carburetor, a throttle valve, a choke valve, means comprising a pair of shafts for controlling said valves, cranks on each of said shafts, a link connecting said cranks, the ends of said 35 link being pivoted to said cranks at different angles with respect to said valves, and the crank on the throttle valve passing over a dead center when the throttle is in approximately one-third open 40 position.

2. In a carburetor, means forming a mixing conduit, a throttle valve for controlling the discharge of mixture from said conduit, a choke valve for controlling the admission of air to said 45 conduit, a suction operated nozzle discharging fuel into said conduit between said throttle and choke valves, thermostatic means for controlling the position of said choke valve to restrict the admission of air when the temperature is low, suction operated means for admitting air to said carburetor when said choke valve is closed, and means connecting said throttle and choke valves for opening said choke valve at least partially when said throttle valve is fully opened.

3. In a carburetor, a throttle valve, a choke valve, a nozzle for discharging fuel into said carburetor between said choke and throttle valves, valve means for controlling the admission of fuel to said nozzle, operating connections between said 50 throttle valve and said fuel control valve and operating connections between said throttle valve and said choke valve, and heat responsive means for controlling said choke valve.

4. In a carburetor, a throttle valve, a choke valve, a nozzle for discharging fuel into said carburetor between said choke and throttle valves, valve means for controlling the admission of fuel to said nozzle, operating connections between 55 said throttle valve and said fuel control valve, and operating connections between said throttle valve and said choke valve, heat responsive means for controlling said choke valve, and suction operated means for admitting air to said carburetor when said choke valve is closed.

5. In a carburetor, a choke valve, a mixture heating chamber, means for controlling the application of heat to said chamber, a heat responsive element, and connections from said heat responsive element for operating both said heat controlling means and said choke valve.

6. In a carburetor, means forming a mixing conduit, a heating device for heating the mixture discharged from said conduit, a choke valve for admitting air to said conduit, a throttle valve in 10 said conduit, a suction operated nozzle between said choke valve and said throttle, means for controlling the application of heat to said mixture, heat responsive means for operating said choke valve, and operating connections between said 15 heat responsive means and said heat controlling means, said operating connections being constructed and arranged to close said heat controlling means after said choke has been opened, and to close said choke after said responsive means 20 has been opened.

7. In a carburetor, means forming a mixing conduit, a choke valve controlling the admission of air to said conduit, a throttle controlling the discharge of mixture from said conduit, a heating device for heating mixture discharged by said conduit, heat responsive means for controlling said choke, said heat responsive means also controlling said heating device, and connections for positively 25 causing an opening movement of said choke 30 valve when said throttle is opened.

8. In a carburetor, means forming a mixing conduit, a choke valve controlling the admission of air to said conduit, a throttle controlling the discharge of mixture from said conduit, a heating device for heating mixture discharged by said conduit, heat responsive means for controlling said choke, said heat responsive means also controlling said heating device, connections for positively 35 causing an opening movement of said choke 40 valve when said throttle is opened, valve means for controlling the admission of fuel to said fuel conduit, and an operating connection between said throttle valve and said fuel valve.

9. In a carburetor, a choke valve, a heating device comprising a chamber through which fuel mixture is passed for heating purposes and a valve controlled heating conduit for applying heat to said chamber, a heat responsive element mounted adjacent said chamber, and means operated by said heat responsive element for controlling said choke valve and said heat controlling valve.

10. In a carburetor, a choke valve, a heating device comprising a chamber through which fuel mixture is passed for heating purposes and a valve controlled heating conduit for applying heat to said chamber, a heat responsive element mounted adjacent said chamber, means operated by said heat responsive element for controlling said choke valve and said heat controlling valve, said choke valve being operated during full open movement of the said heat responsive element, and said heat responsive element being operated during another portion of said movement.

11. In a carburetor, a choke valve, a heating device comprising a chamber through which fuel mixture is passed for heating purposes and a valve controlled heating conduit for applying heat to said chamber, a heat responsive element 70 mounted adjacent said chamber, means operated by said heat responsive element for controlling said choke valve and said heat controlling valve, said choke valve being operated during one portion of the movement of said heat responsive ele- 75

ment, and said heat controlling valve being operated during another portion of said movement.

12. In a carburetor, a choke valve, a heating device comprising a chamber through which fuel mixture is passed for heating purposes and a valve controlled heating conduit for applying heat to said chamber, a heat responsive element mounted adjacent said chamber, means operated by said heat responsive element for controlling said choke valve and said heat controlling valve, said choke valve being operated during one portion of the movement of the said heating element, said heat controlling valve being operated during another portion of said movement, and means for permitting continued movement of said heat responsive element in a direction to close said heat controlling valve after said choke valve has been fully opened.

13. In a device of the class described, means forming a mixing conduit, a heating device for heating the mixture in said mixing conduit, valve means for controlling the flow of heating fluid through said heating device, an unbalanced weight for normally holding said heat controlling valve means in open position, and a heat responsive element for closing said heat controlling valve means when a predetermined temperature has been reached.

14. In a device of the class described, means forming a mixing conduit, a heating device for heating the mixture in said mixing conduit, valve means for controlling the flow of heating fluid through said heating device, an unbalanced weight for normally holding said heat controlling valve means in open position, a heat responsive element for closing said heat controlling valve means when a predetermined temperature has been reached, a choke valve for controlling the admission of air to said carburetor, and an operating connection between said heat responsive element and said choke valve.

15. In a device of the class described, means forming a mixing conduit, a heating device for heating the mixture in said mixing conduit, valve means for controlling the flow of heating fluid through said heating device, an unbalanced weight for normally holding said heat controlling valve means in open position, a heat responsive element for closing said heat controlling valve means when a predetermined temperature has been reached, a choke valve for controlling the admission of air to said carburetor, an operating connection between said heat responsive element and said choke valve, a throttle valve for said mixing conduit, and an operating connection between said throttle valve and said choke valve.

16. In a carburetor for internal combustion engines, a throttle valve, a choke valve, said choke valve including a transverse shaft carrying a suction operated valve portion, a heat responsive device normally controlling the movements of said valve portion in conjunction with the suction, means for interfering with the initial opening movement of said valve portion by suction, said means being effective only during the earlier stages of the opening of the choke valve, and a connection between said throttle and choke valve, said connection being constructed and arranged so that when said throttle is fully opened, the choke valve will be opened to a position in which it is no longer affected by said interfering means.

17. In a carburetor for internal combustion engines, a throttle valve, a choke valve, said choke valve including a shaft and a suction operated valve mounted thereon, a heat responsive device

connected to said shaft for normally controlling the position of said choke valve in conjunction with the suction applied thereto, a device constructed and arranged to operate only when said choke valve is in substantially closed position for interfering with the opening thereof by suction, and connections between the throttle and choke valves for opening the choke valve beyond the operative range of said device whenever the throttle is moved to fully open position.

18. In a carburetor for internal combustion engines, means forming a mixing conduit having an air inlet and a mixture outlet, choke valve means controlling said air inlet, a throttle valve controlling said mixture outlet, said choke valve means including a valve member movable toward open position by suction, a heat responsive device connected to said choke valve means and adapted to apply a force to hold said member in closed position against the force of suction, additional means for resisting the opening of said choke valve member by suction, said additional means being constructed and arranged to operate only when said suction operable valve member is in proximity to its closed position, and a connection between said throttle and said choke valve mechanism, said connection being constructed and arranged to open said choke valve member to a point beyond the effective range of said additional means.

19. In a carburetor, a suction operable choke valve, means resisting the operation of said choke valve by suction, said resisting means being effective only when said choke valve is in closed or nearly closed position, heat responsive means for closing said choke valve when the temperature is low, a throttle valve, and connections between said throttle and choke valves for forcing said choke valve to partially open position when said throttle valve has been moved to a predetermined position.

20. In a carburetor, a choke valve, a heat responsive device connected to said choke valve and adapted to move it to closed position when the temperature is low, said choke valve being normally operable in response to suction, a device constructed and arranged to interfere with the opening of said choke valve by suction when said valve is near its closed position, said device being substantially ineffective in other operating positions of the choke valve, a throttle valve and connections between said throttle valve and said choke valve for opening said choke valve to such a degree that said device is no longer effective.

21. In a carburetor, a choke valve, a heat responsive device for controlling said choke valve, said choke valve being normally operable in response to suction, latch means for resisting the opening of said choke valve by suction, said latch being ineffective except when said choke valve is in substantially closed position, a throttle valve, and connections between said throttle valve and said latch.

22. In a carburetor, means forming a mixing conduit having an air inlet, a choke valve mechanism for controlling said air inlet, said mechanism being operable by heat and by suction to open said inlet, resistance means for interfering with the operation of said valve mechanism by suction when the mechanism is in position to close said inlet, a throttle valve and means connected to said throttle valve for disengaging said resistance means.

23. In a device of the class described, an exhaust passage, a valve in said passage, yielding

means tending to move the valve to one position, and a thermostatic coil spring for overcoming said yielding means, to move the valve to another position when a predetermined temperature is exceeded.

5 24. In a device of the class described, means forming a mixing conduit, a heating device for heating the mixture in said mixing conduit, valve means for controlling the flow of heating fluid through said heating device, an unbalanced weight for normally holding said heat valve in one position, a heat responsive element for moving said heat valve to another position when a predetermined temperature has been reached, a choke valve for controlling the admission of air to said carburetor, and an operating connection between said heat responsive element and said choke valve.

10 25. In a device of the class described, means forming a mixing conduit, a heating device for heating the mixture in said mixing conduit, valve means for controlling the flow of heating fluid through said heating device, an unbalanced weight for normally holding said heat valve in one position, and a heat responsive element for moving said heat valve to another position when a predetermined temperature has been reached.

15 26. In a carburetor for internal combustion engines, a choke valve, a throttle valve, a lost motion connection between said throttle valve and said choke valve for at least partially opening said choke valve when said throttle valve is either fully closed or fully opened, said lost motion connection permitting the closure of said choke valve when the throttle is in an intermediate position.

20 27. In combination with an internal-combustion engine having a carburetor, a choke-valve for said carburetor, a throttle-valve for said carburetor, and means operated with the throttle-valve as it approaches both limits of its range of adjustment for limiting closing movement of said choke-valve.

25 28. In a control mechanism for a carburetor having a choke valve and a throttle, the combination of a thermostat for governing the degree of opening of the choke valve as a function of temperature, and means connecting the choke valve and throttle for partially opening the valve when the throttle is fully opened and also when the throttle is fully closed.

GEORGE M. BICKNELL.
